(57) **CLAIM**

The ornamental design for a drainage cuff, as shown and described.

DESCRIPTION

FIG. 1 is a top perspective view of a drainage cuff showing my new design in an environment of a cap for a drainage pipe;

FIG. 2 is a bottom perspective view of the drainage cuff of FIG. 1;

FIG. 3 is a front elevational view of the drainage cuff of FIG. 1;

FIG. 4 is a rear elevational view of the drainage cuff of FIG. 1;

FIG. 5 is a right side elevational view of the drainage cuff of FIG. 1;

FIG. 6 is a left side elevational view of the drainage cuff of FIG. 1;

FIG. 7 is a top plan view of the drainage cuff of FIG. 1;

FIG. 8 is a bottom plan view of the drainage cuff of FIG. 1;

FIG. 9 is a top perspective view of a drainage cuff showing my new design in an environment of a drainage pipe cap with a pop-up emitter;

FIG. 10 is a bottom perspective view of the drainage cuff of FIG. 9;

FIG. 11 is a front elevational view of the drainage cuff of FIG. 9, the right side, left side, and rear side elevational views being mirror images thereof;

FIG. 12 is a top plan view of the drainage cuff of FIG. 9;

FIG. 13 is a bottom plan view of the drainage cuff of FIG. 9;

FIG. 14 is a top perspective view of a drainage cuff showing my new design in an environment of an adaptor for drainage pipes;

FIG. 15 is a bottom perspective view of the drainage cuff of FIG. 14;

FIG. 16 is a front elevational view of the drainage cuff of FIG. 14, the right side, left side, and rear side elevational views being mirror images thereof;

FIG. 17 is a bottom plan view of the drainage cuff of FIG. 14; and,

FIG. 18 is a top plan view of the drainage cuff of FIG. 14. The dashed broken lines depict environment only and form no part of the claimed design. The dot-dash broken lines depict bounds of the claimed design and form no part thereof.
